UNITED STATES PATENT OFFICE.

PAUL LÉON HULIN, OF GRENOBLE, FRANCE, ASSIGNOR TO SOCIÉTÉ D'ELECTRO-CHIMIE, OF PARIS, FRANCE, AND PAUL LÉON HULIN, OF GRENOBLE, FRANCE.

MEANS FOR THE ELECTROLYTIC MANUFACTURE OF SODIUM.

979,497.

Specification of Letters Patent. Patented Dec. 27, 1910.

Application filed October 27, 1908. Serial No. 459,728.

To all whom it may concern:

Be it known that I, PAUL LÉON HULIN, of 6 Rue Félix Poulat, Grenoble, Isère, Republic of France, engineer, have invented 5
5 Means for the Electrolytic Manufacture of Sodium, of which the following is a full, clear, and exact description.

The present invention has for its object to provide practical means for the electrolysis of mono-hydrated caustic alkalies on an 10 industrial scale and is particularly applicable to the manufacture of sodium by the electrolysis of fused caustic soda.

When fused caustic soda is treated by the 15 electric current the oxygen passes to the anode while the hydrogen and the sodium collect at the cathode and together rise to the surface. Nevertheless the formation of these products may in practice present abnormalities; thus the oxygen may attack the anode too vigorously and the sodium may 20 re-dissolve or may be incapable of separation unless the operation be conducted under specialized conditions and with the aid of 25 appropriate apparatus. The principal difficulty would appear to be attributable to the intimate association of the freshly produced sodium and hydrogen. The formation of 30 this gas at the cathode causes an ebullition which, owing to the lightness of the metal disperses the latter into the electrolyte and subdivides it into minute particles which, having no common ascensional tendency, are 35 incapable of collecting in a chamber assigned for the purpose. Under these conditions the sodium undergoes very rapid oxidation both in the bath, throughout which it is so finely dispersed as to practically constitute an emulsion, and also at the surface 40 where it is in a very finely divided state. Hence it is only possible to collect a very small proportion of the actual yield. The practical solution of the problem was furnished in the first instance by Castner who 45 invented a special apparatus. By rigorously limiting the temperature of the bath and by the use of a special diaphragm of metallic gauze adapted to confine the disengaged hydrogen and sodium to a narrow chamber, 50 Castner was able to cause the globules of sodium to coalesce into a buoyant fused mass which could be easily removed by means of appropriate ladles or the like.

The apparatus, together with its adjuncts, which constitutes the subject of the present 55 invention is represented in the accompanying drawings wherein—

Figure 1 is a horizontal section on line 3—3 of Fig. 2. Fig. 2 is a vertical section on line 1—1 of Fig. 1. Fig. 3 is a plan 60 view of the apparatus, the separator being removed, while Fig. 4 is a vertical section on line 2—2 of Fig. 3, showing a modification of the separator. Fig. 5 is a horizontal section showing the heating device. Figs. 6 65 and 7 are detailed views of various adjuncts of the apparatus. Fig. 8 is a plan view and Fig. 9 a vertical section of a modification 70 of the apparatus provided with flat electrodes.

The apparatus comprises a vat A of cast-iron or steel of any appropriate cross section, but preferably cylindrical or rectangular with rounded angles. A cylinder B of iron or laminated or forged steel is supported in the vat by means of arms C, C of the same material, which also serve to conduct the current (of positive polarity) to the said cylinder. This cylinder B constitutes the anode of the apparatus. In the 75 center of the vat is suspended a range of rods or strips of copper which constitutes the cathode, a predetermined annular space separating the electrodes. The cathode is thus formed of a circular group of vertical 80 rods t, t, t of copper mounted upon a crown D of the same metal around its periphery (Figs. 1-2, 3, 4 and 6). A central support d with downwardly extending arms suspends 85 this crown at the proper level and supplies 90 to it the current of negative polarity. This support d is fixed at its upper end to a suitable support through the medium of a nut or the like, permitting the dismounting of 95 the cathode which should ordinarily remain fixed in position. A circular ring E of sheet-iron or steel is suspended concentrically with the electrodes. This ring which is partially immersed in the electrolyte produces at the surface of the bath an effective 100 separation between the oxygen rising from the anode (which escapes externally) and the hydrogen together with the sodium rising from the cathode (which collects in the interior). The vat A rests upon a stone- 105 ware base F, the latter having an interior

chamber which serves to contain a long and thick heating coil of laminated iron G whose extremities terminate in two prolongations of larger section leading out of the apparatus by means of which a current of great intensity can be conducted thereto.

An insulating envelop such as H serves to prevent radiation as far as possible so as to permit of the bath of caustic soda being 10 maintained at a fusion temperature.

In order to set the apparatus in action the vessel A is filled with caustic soda in fragments and the electric current is caused to traverse the conductor G; the intensity of 15 the current is regulated so as to bring the conductor to red-heat. The heat disengaged is absorbed by the metal of the vat and the soda which it contains becomes fused. As soon as the vessel is full of liquefied soda the 20 current is stopped flowing in the heating circuit G and the apparatus is ready for work.

The production of sodium is initiated by 25 passing a continuous current, whose intensity is proportioned to the dimensions of the apparatus and under a pressure of about 5 or 6 volts, the resistance which the current experiences in traversing the bath causing the development of sufficient heat to maintain 30 the soda in the fused state. Under the electrolytic action of the current, free oxygen is formed at the anode and is disengaged at the surface externally of the separator E (Fig. 2), while the hydrogen 35 and sodium simultaneously escape from the cathode in globules and both appear at the surface of the bath in the interior of the ring E. The sodium collects in drops resembling melted white wax, and it is removed by 40 means of a perforated ladle which only permits the passage of the fused soda.

The apparatus is charged periodically 45 with soda to replace that which has been decomposed. The mean level of the bath is indicated at J. The essential features of this apparatus may be stated as follows.

The cathode formed of spaced rods, constitutes a great spherical development of the two electrodes, but whereas the anode has a 50 large surface actually exposed to electrolytic action, the cathode, whose activity is concentrated upon its rods, presents on the contrary only a small electrolyzing surface. The practical results of these arrangements 55 are as follows.

The anode, by reason of its large surface, does not suffer any appreciable oxidation and this permits of employing sheet iron or mild steel which will last for a long time. 60 This great development of the anode in conjunction with the distribution of the rods, offers a large area for the current to pass to the bath, so that sufficient space may be allowed between the anode and cathode to 65 allow the oxygen and the sodium to reach

the surface at their respective sides without the employment of a diaphragm. The subdivision of the cathode into small elements in the form of vertical rounded rods has a special efficacy. The sodium which is 70 formed around each rod produces an envelop which surrounds it and grows by accretion and reaches the surface exclusively in the form of globules of a size great enough to enable it to offer sufficient resistance to the environmental destructive actions. Thus the employment of these rods not only serves to guide the ascent of the sodium, but also enables the use of a diaphragm to be dispensed with. After the 80 apparatus has been in action for a time which may vary between wide limits (12, 24 or 48 hours) a gradual and progressive diminution in the production of the sodium may be observed. The output gradually 85 diminishes up to a 50% reduction and it may also happen that the bath becomes excessively heated, while the formation of sodium becomes insignificant and this without any apparent external cause. 90

According to the invention forming the subject of the present application, it is by renewing the active surface of the cathode that the normal efficiency of an apparatus of this kind is restored. In order to effect 95 this result the electrolyzing current is momentarily stopped and the fixed cathode is detached from its support and is then withdrawn from the bath, whereupon the rods are plunged into water or into an aqueous 100 solution such as soda-lye. After the conclusion of this washing operation, which may be rapidly carried out without any danger (by immersion or by aspersion) the cathode is replaced and fixed in position, 105 the current is restored and the sodium is soon seen to make its appearance in the form of sufficiently large globules. Thus by a periodical washing of the cathode a normal and practically continuous working of an 110 apparatus of this kind may be obtained. This periodical washing operation is an essential feature of the process and constitutes one of the characteristics of the invention. 115

Figs. 4 and 7 represent at E² a modification of the separator formed of a tubulated plate having a rabbeted margin, beneath which the sodium collects and whence it finally passes into the tubulure e from which 120 it may be extracted. By the use of this closed separator the sodium is protected against the action of the surrounding air and the alkaline projections are very attenuated. This collector provided with a 125 lid is preferable to the open ring which it replaces. The apparatus thus constituted admits of various other modifications in its details, for example, it may be constructed with plane parallel electrodes without alter- 130

ing its fundamental characteristics. A transformation of this kind is quite naturally derived from the circular form whereof it is simply a rectilinear truncated development. Figs. 8 and 9 show respectively a plan and a vertical section of an apparatus constructed with multiple, alternate plane electrodes B and t , the whole assemblage having an anode at each side. With this modification all the essential constituent elements of the fundamental type are retained as are also their properties and mode of operation. The vessel wherein the sodium collects, becomes in this arrangement an elongated frame such as E^1 . Furthermore with this modification a closed separator on the principle of that represented at E^2 may be adopted. Each cathode is provided with a separate collector. The anodes B^2 consist of sheet metal strips and the cathodes D^2 have the general shape of a comb or rake. The invention is otherwise independent of the forms, dimensions and detail-arrangements of the various elements which constitute the complete apparatus above described.

Claims:

1. In an apparatus for the manufacture of sodium by the electrolysis of caustic soda, a cathode consisting of spaced vertical rods hanging from and below a common carrier, said carrier being detachably secured to a fixed support and an anode external to said cathode.
2. In an apparatus for the electrolytic manufacture of sodium, a cathode consisting of separated rods hanging below a circular carrier secured detachably to a fixed support, and a cylindrical anode surrounding said cathode.
3. In an apparatus for the electrolytic manufacture of sodium a cathode consisting of vertically disposed separated rods hanging below a common carrier, and a flat col-

lecting dish provided with downwardly flared edges and provided with a sodium pot 45 on its side.

4. In an apparatus for the electrolytic manufacture of sodium a cathode consisting of separated vertical rods hanging below a common carrier, a suspension rod at the 50 center of this common carrier, a flat sodium collector provided with downwardly flared edges provided at its center with an aperture provided with a sleeve for the passage of the cathode carrier and provided on its 55 side with a sodium pot.

5. In an apparatus for the electrolytic manufacture of sodium a cathode consisting of separated vertical rods hanging below a common circular carrier, a suspension rod 60 at the center of this common carrier, a flat circular sodium collector provided with downwardly flared edges, provided at its center with an aperture provided with a sleeve for the passage of the cathode carrier and provided on its side with a sodium pot. 65

6. In an apparatus for the electrolytic manufacture of sodium, a cathode consisting of separated vertical rods hanging below a common carrier, a sodium collecting dish, a vat and a zig-zag shaped electrical heating device disposed under the vat. 70

7. In an apparatus for the electrolytic manufacture of sodium, a cathode consisting of separated vertical rods suspended from a common carrier, a sodium collecting dish, a vat, and an electric heater under the vat. 75

The foregoing specification of my means 80 for the electrolytic manufacture of sodium signed by me this 16th day of October, 1908.
